UNITED STATES PATENT OFFICE.

GEORGE W. GREEN, OF WAKEMAN, OHIO.

SCAFFOLD.

SPECIFICATION forming part of Letters Patent No. 249,757, dated November 22, 1881.

Application filed July 21, 1881. (No model.)

To all whom it may concern:

Be it known that I, G. W. GREEN, of Wakeman, in the county of Huron and State of Ohio, have invented certain new and useful 5 Improvements in Scaffolds; and I do hereby declare that the following is a full, clear, and exact description of the invention, which will enable others skilled in the art to which it app pertains to make and use the same, reference 10 being had to the accompanying drawings, which form a part of this specification.

Figure 1 is a perspective view of my improved scaffolding ready for use. Fig. 2 is a 15 vertical sectional view, and Fig. 3 is a detail view.

Corresponding parts in the several figures are denoted by like letters of reference.

This invention relates to adjustable and extensible scaffolds for the use of bricklayers, 20 carpenters, painters, &c., while working upon buildings in the course of or after erection, and for other purposes; and the invention consists in the improved construction, arrangement, and combination of parts, which will be 25 hereinafter fully described, and particularly pointed out in the claim.

In the drawings hereto annexed, A represents the main frame or base, which consists of vertical sides or uprights B B and slanting 30 end frames, C C', the upper ends of which abut against the said vertical side pieces, as shown. Horizontal braces D are provided to connect the side pieces with the end frames, and one of the latter, C, is provided with rungs E, like 35 an ordinary ladder.

The inner sides of the uprights B are provided with cleats F, forming guides for the vertically-sliding extension of my improved scaffolding. The said extension consists of an 40 ordinary ladder, L², the sides G of which slide in the guides or ways formed by the cleats F, said sides being connected by rounds or rungs H. A platform, I, is secured to the upper ends of the sides G, the particular construction of 45 which platform will be hereinafter more fully described and claimed.

Upon the inner sides of the uprights B are secured or formed brackets J, having pulleys K, and a shaft, L, is journaled in suitable boxes

mounted in cross-pieces M, near the lower ends 50 of the end frames, C C', as shown. Ropes, cords, or chains N are attached to the said shaft L, rove over the pulleys K, and attached to the lower ends of the vertically-sliding extension-ladder, which may thus be hoisted or 55 elevated by simply operating the shaft L by means of a crank, O, with which it is provided.

The sides or uprights B are provided near their upper ends with slots P, in which are pivoted spring-pawls Q, engaging notches R 60 in the sides of the extension-ladder, which may thus be retained at any desired elevation. The said spring-pawls may, however, be held disengaged from the extension-ladder by means of latches S, pivoted to the sides B, and capable of holding the lower ends of the pawls or 65 levers closely against said sides, thus disengaging their upper ends from the notches R.

The platform I, which forms the top of the extension-ladder, is provided on its under side 70 with eyes or staples T, in which props U, having hooks V, may be adjusted to support the scaffolding while in use. Said props are provided at their lower ends with points W, which may be straight or hooked, according to the 75 nature of the ground or pavement upon which the scaffolding is placed.

A slide, X, adjustable by a set-screw, Y, is arranged between cleats Z upon the under side of the platform. Said slide will serve as a support in cases where the scaffolding is placed 80 against a wall, which makes it impracticable to use one of the props or supports U.

A' is a bracket secured on top of the platform I, and provided with a hook, B', upon 85 which a pulley may be hung, to enable buckets, hods, &c., to be conveniently raised or lowered.

From the foregoing description, taken in connection with the drawings hereto annexed, the 90 operation and advantages of my invention will be readily understood. It may be conveniently used, either singly or in pairs, in which latter case a plank may be supported upon the top platforms, which may be readily adjusted vertically to the desired height. It is simple, inexpensive, and easily manipulated.

Having thus described my invention, I claim

and desire to secure by Letters Patent of the United States—

As an improvement in scaffolds, the combination, with the frame B C D E, constructed as herein described, of the vertically-adjustable ladder L², having platform I, provided with a laterally-adjustable slide or brace, X, substantially as and for the purpose shown and specified.

In testimony that I claim the foregoing as to my own I have hereto affixed my signature in presence of two witnesses.

GEORGE W. GREEN.
